(57) **CLAIM**

The ornamental design for an ultrasound device, as shown and described.

DESCRIPTION

FIG. 1 is a top left front perspective view of an ultrasound device showing our new design;

FIG. 2 is a back side view thereof;

FIG. 3 is a front side view thereof;

FIG. 4 is a right side view thereof;

FIG. 5 is a left side view thereof;

FIG. 6 is a top view thereof; and,

FIG. 7 is a bottom view thereof.

The dashed lines illustrate portions of the ultrasound device that form no part of the claimed design. The dot-dash lines show the boundaries of the claimed design and also form no part of the claimed design.

1 Claim, 5 Drawing Sheets
